UNITED STATES PATENT OFFICE.

HANS C. HANSEN, OF BOSTON, MASSACHUSETTS.

PIN-HOLE-PERFORATING MACHINE.

SPECIFICATION forming part of Letters Patent No. 364,248, dated June 7, 1887.

Application filed February 28, 1887. Serial No. 229,172. (No model.)

To all whom it may concern:

Be it known that I, HANS C. HANSEN, a citizen of the United States, and a resident of Boston, in the county of Suffolk and State of 5 Massachusetts, have invented new and useful Improvements in Pin-Hole-Perforating Machines, of which the following, taken in connection with the accompanying drawings, is a specification.

10 This invention relates to improvements in pin-hole-perforating machines for the purpose of perforating sheets of paper, card-board, &c., and it is carried out as follows, reference being had to the accompanying drawings, where—

15 Figure 1 represents a central longitudinal section of the improved machine. Figs. 2 and 3 represent, in detail and full size, respectively, end and side views of the perforating device.

Similar letters refer to similar parts wherever they occur on the drawings.

20 *a* is the metal frame of the machine, and *a'* is its goose-neck, as is usual in machines of this kind.

b is the driving-shaft, located in bearings *a''*, 25 *a'* and *a'* in the goose-neck *a'*, as shown in Fig. 1, and to the forward end of said shaft is secured, by means of the nut *b'*, the punch-wheel *C*, provided with the radial punches *c*, as shown.

30 *b''* is a collar on shaft *b*, at the rear of goose-neck bearing *a'*, to prevent a longitudinal movement of said shaft in its bearings. To the rear end of shaft *b* is secured the fast pulley *b'*, to which a rotary motion is conveyed 35 by means of a belt, as usual.

b' is the loose pulley, located on shaft *b*, between the fast pulley *b'* and the rear goose-neck bearing *a''*, as shown in Fig. 1.

40 *D* is the work-supporting table. (Shown in Figs. 1 and 2.)

Below the rotary punch-wheel *C* is located, on shaft *e'*, the die-wheel *E*, having radial perforations *e e* through its flanged periphery, corresponding in size and number to the radial punches *c c* on the rotary punch-wheel *C*, as is common on machines of this kind. The die-wheel shaft *e'* is supported in bearings *f f'*, cast in one piece with the base-plate *f''*, which latter is secured to frame *a* by means of set-screw *f''* and bridge-plate *f''*, (shown in Fig. 1,) or equivalent or well-known devices.

Outside of the bearings *f f'* for the die-wheel shaft *e'* are secured to the latter the feed or guide wheels *G G*, having peripheral grooves *g*, (shown in lower right-hand portion of Fig. 3,) in which are laid the annular rubber bands *g' g'*, as shown, to produce a proper friction in connection with other devices, hereinafter to be described, for feeding and guiding the material to be perforated.

55 A positive rotary motion is imparted to the die-wheel *E* and guide or feed wheels *G G* from the punch-wheel *C* by the radial punches *c c* entering the radial perforations in the die-wheel *E*, as shown in Fig. 1. The die-wheel shaft *e'* is free to adjust itself longitudinally in its bearings *f f'*, so as to compensate for any inequalities in the positions of the punches *c c* relative to the perforations *e e* in the die-wheel, and for this purpose each bearing *f* is 60 made a little narrower than the distance between the hub of the die-wheel *E* and inside of the respective feed and guide wheels *G G*, as shown in Figs. 1 and 3.

65 To the goose-neck bearing *a'* is secured, by means of ears *h h'* and screws *h' h'*, the curved metal plate *H*, as shown, said plate having a slot, *h''*, (shown in Fig. 1,) through which passes a portion of the punch-wheel *C*, which plate serves for the purpose of disengaging the perforated paper from the 70 punches *c c*, and preventing it from being carried around the said punch-wheel. In slots *H' H'* in the ends of said plate *H* are loosely journaled the reduced portions *k k* of the auxiliary feed and guide rollers *K K*, as shown in 75 Figs. 2 and 3, and each opposite pair of such rollers is provided with an elastic endless band, *k'*, that lies in contact with the friction-band *g* on its corresponding roller or guide-wheel *G*, as shown in Figs. 2 and 3.

80 I make on opposite of the curved plate *H* a pair of inverted L-shaped guides, *h'' h''*, directly above the respective feed or guide wheels *G G*, as shown in the drawings, for the purpose of properly guiding the elastic bands *k' k'* to 85 and from their respective rollers *K K*, and thus preventing said bands from running off said rollers.

85 As the guide and feed wheels *G G* are rotated, their friction-bands *g g* impart a continuous rotary motion to the rollers *K K* and their friction-bands *k' k'*.

If the paper to be perforated is of sufficient width, it is introduced between both the rollers or guide-wheels G G and the endless carrying-bands k' k', and the punch and die wheels 5 C E arranged between them, by which the paper to be perforated is properly fed and guided, and prevented from being carried to the right or left of a true linear motion.

If the paper to be perforated is not wide 10 enough to be carried by both the wheels G G, either one of them, in connection with the corresponding ends of rollers K K and one of the bands k', will serve the purpose of properly guiding the paper as it is being fed forward 15 by the punch and die wheels C and E.

The operation of the machine is as follows: The shaft b and punch-wheel C is set in a rotary motion by the means described, causing the die-wheel E and guide-wheels G G to be 20 correspondingly rotated positively and with equal velocity, and motion imparted to the bands k' k' by the wheels G G and their bands g' g'. The paper is then fed onward on the table D, and introduced between the wheels 25 G G and the endless carriers or bands k' k', causing the paper to be fed and guided to the punch and die wheels C E, where the punching takes place, after which the now finished paper is disengaged from the punches c c by 30 being carried below the curved plate H. By this construction and arrangement of parts

as described the paper to be perforated is most positively fed and guided to and from the perforating devices without any liability of being carried to the right or left of the central line in which the perforations are to be made, and by these means I am able to produce most accurate work.

35

Having thus fully described the nature, construction, and operation of my invention, I 40 wish to secure by Letters Patent, and claim—

1. In a perforating-machine, the rotary punch-wheel C, having radial punches c c, in combination with the die-wheel E and guide-wheels G G, secured to the longitudinally-adjustable shaft e', and having the annular friction-bands g' g', and the loosely-rotating rollers K K, having the endless bands k' k', as and for the purpose set forth.

45

2. The die-wheel E and guide-wheels G G, 50 secured to the shaft e', in combination with the stationary plate H, its rollers K K, endless bands k' k', and inverted L-shaped band-guides h', as and for the purpose set forth.

55

In testimony whereof I have signed my name to this specification, in the presence of two subscribing witnesses, on this 25th day of February, A. D. 1887.

HANS C. HANSEN.

Witnesses:

ALBAN ANDRÉN,
HENRY CHADBOURN.
